CLAIM

The ornamental design for a front portion of a motor vehicle and/or toy replica thereof, as shown and described.

DESCRIPTION

FIG. 1 is a front perspective view of a front portion of a motor vehicle and/or toy replica thereof showing our new design;

FIG. 2 is a rear perspective view thereof;

FIG. 3 is a right-side view thereof;

FIG. 4 is a top view thereof;

FIG. 5 is a front view thereof; and,

FIG. 6 is a rear view thereof.

In the photographs, the claimed design is shown darker than the surrounding environment subject matter, the latter being shown lighter for contrast and does not form no part of the claimed design.
